Martin Metcalf

United States Patent Office.

MARTIN METCALF, OF GRAND RAPIDS, MICHIGAN.

Letters Patent No. 78,677, dated June 9, 1868.

IMPROVED MACHINE FOR GROOVING AND SWAGING SHEET METAL.

The Schedule referred to in these Letters Patent and making part of the same.

TO ALL WHOM IT MAY CONCERN:

Be it known that I, MARTIN METCALF, of the city of Grand Rapids, in the county of Kent, and State of Michigan, have invented certain new and useful Improvements in Machines for Grooving and Swaging Sheet Metals; and I do hereby declare that the following is a full and exact description of the same, reference being had to the accompanying drawings, and to the letters of reference marked thereon, in which—

Figure 1 is a profile view of the machine, with a length of pipe represented passing into the same.

Figure 2 is a front view of the machine, showing the construction and operation of the rollers for making the seam.

The nature of my invention consists in providing a sheet-metal grooving and swaging-machine with suitable grooving, swaging, and setting-down rollers, and arranged in such a manner that the plate to be grooved or cylinder to be locked and swaged, is drawn into the machine between two rollers, being grooved as it passes in, where it is swaged or beaded, and its small end swaged in, so as to readily enter another cylinder or pipe, and in returning out of the machine the seam is closed down perfectly tight and smooth, so that a perfectly-finished length of pipe is delivered from the machine at one operation of the same.

To enable others skilled in the art to construct and use my invention, I will now proceed to describe its construction and operation.

In the drawings, A A, fig. 1, represent the main frame of the machine.

C C C C, fig. 2, represent a small frame, or two clamps, which carry the groove-roller 1, the setting-down roller 2, with the cog-wheels 1' 2' 3. The bolt *d* fastens these clamps together or in place, one on each side of the front end of upper frame-bar A, passing through the latter, and forming a centre, on which the small frame rocks to and fro by the movements of the handled right-hand clamp, as hereafter described.

b represents a small lever, with a spring under its upper end, and pin in its opposite ends, the latter passing through a hole made in the clamp C, so that the pin may enter the slot *f* in the frame A A, fig. 1.

A spring, *g*, fig. 1, shown by the dotted line, fastened to the frame A, and acting on the centre-bolt *d*, figs. 1 and 2, serves to hold the small frame and wheels up, while the thumb-screw *h*, acting on the box and shaft *d*, fig. 1, shown by the dotted lines, regulates the distance between the centre of bolt *d*, fig. 2, and wheel 4 in lower part of frame A A, also shown in fig. 1.

A crank, *e*, made fast to the loose cog-wheel 3, acts on the cog-wheels 1' and 2', and operates the wheel 4, by means of the friction alternately of the groove-wheel and setting-down wheel, attached to them, as shown in fig. 2.

B B, fig. 1, represent the ordinary male and female swage-rollers, with suitable shafts, crank, and wheels to operate them, the shafts passing through the centre of the rear end of the machine, with spring between them, as shown by the dotted lines. These swage-rollers are bevelled on their extreme rear ends, the upper one made larger and the lower one smaller, for the purpose of contracting the small end of a pipe. These rollers are operated by the crank, *I*, made fast to the upper shaft. The eccentric-lever *D*, fig. 1, forces them together, while the spring (dotted lines) lifts them apart when the lever is up, as represented.

A perpendicular passage-way is made through the lower part of frame, immediately under the swage-rollers B B, fig. 1, for any scales that may fall from the metal being swaged, as shown by the dotted lines. This machine is made fast to the workman's bench by means of the bolt *H* attached to the rear under side of the frame A A and hand-nut *m*.

In operating this machine, let us suppose we wish to make a length of pipe complete. Having provided ourselves with a length of the same, duly prepared by first having been formed and its locks turned, the operator, standing at the right-hand front end of the machine, in the proper position to operate the crank *e* with the right hand, while in the left he holds the pipe, with its smaller end at the entrance between the rollers 1 and 4, with the levers in the position represented in fig. 1. The groove-roller will now be in its proper place on the convex roller 4 in the lower arm of frame A. With the locks together on the entering end, at least, the operator will

turn the crank in the direction shown by the arrow, fig. 1, which will draw the seam through between the rollers and on to the frame-arm carrying the convex roller 4, as shown by the dotted lines, at the same time forming a very perfect lock throughout its whole length.

Having passed the pipe through between the rollers on to the arm A of large frame, the upper and small end of pipe will have entered between the swage-rollers B B. The operator will now press down the eccentric-lever D, (either directly with the hand or by stepping on a treadle,) so as to imprint the pipe, when, by turning the crank I, fig. 1, the small end of the pipe will be beaded and swaged in or contracted, so as to readily enter the large end of another pipe, at the same time that it is being swaged in the ordinary way, while the arm A holds the pipe in position, so as to insure its being properly done without the aid of the operator other than that of turning the crank.

The operator will now release the pipe from the grasp of the rollers B B, by throwing back the lever D, and resume his former position at the front of the machine. Taking hold of the right-hand lever-end of the clamp C C, fig. 1, with the left hand, a slight pressure on the lever b will release the pin in its opposite end from the slot f, so that the small frame may be oscillated by throwing the lever back until the side of clamp C C, suitably shaped for that purpose, strikes a pin, n, in the frame A. The little finger lets loose now of the small lever b, and the spring on its under side forces the pin in its opposite end into the slot f of the large frame A, securely holding the parts in this position.

By this movement the small frame will be oscillated, so as to bring the setting-down or concave wheel 2, fig. 2, opposite and attached to the cog-wheel 2', fig. 1, into the place previously occupied by the groove-wheel 1, fig. 2, while the groove-wheel will be carried outward toward the operator, as shown by the dotted lines, fig. 1. Taking hold of the small end of the pipe with the left hand on the left-hand side of the machine, using a little force, while with the right hand the crank is turned in the same direction as before, the seam is very rapidly and perfectly closed down, as the length of pipe is returning out of the machine, thus completing the process of locking and finishing a joint of pipe or other seam at one operation, without the labor, noise, or a blow of hammer or mallet.

The thumb-screw h is for adjusting the wheels to any thickness of metal. The crank, e, is placed on the loose cog-wheel 3, instead of on the cog-wheel 1' or 2', fig. 1, for the purpose of placing it up out of the way of flat surfaces, when it is desired to groove such, or any sheet-metal cylinders of large diameter.

Disclaimer.

I do not claim broadly the construction of a sheet-metal grooving and setting-down machine with open frame, and the grooving-roller 1, fig. 2; nor do I claim the use separately of the roller 1, 2, or 4; but

What I do claim, and desire to secure by Letters Patent of the United States, is—

1. The peculiar arrangement and construction of the small frame C C C C, with the rollers 1 2, and the oscillating-shaft d, fig. 2, substantially as and for the purpose specified.
2. The construction and arrangement of the small frame C C C C, with the rollers 1 2 and the shaft d, in connection with the small-lever b, slot f, and stop-pin n, substantially as and for the purpose described.
3. The combination of the parts constituting the small frame, with its shaft d, rollers 1 and 2, cog-wheels 1' 2' 3, lever b, and thumb-screw h, with the large frame A A, the stationary roller 4, and swage-rollers B B, and eccentric-lever D, substantially as and for the purposes specified.

In testimony that I claim the foregoing, I have hereunto set my hand and seal, this first day of February, A. D. 1868.

MARTIN METCALF. [L. s.]
